Primary Examiner — Christian P. McLean*Assistant Examiner* — Jessica Lynn Devilbiss(74) *Attorney, Agent, or Firm* — Bold IP, PLLC;
Christopher Mayle(57) **CLAIM**

The ornamental design for a window shade set, as shown.

DESCRIPTION

FIG. 1 is a front perspective view of a window shade set in accordance with the present invention;

FIG. 2 is a front view thereof;

FIG. 3 is a rear view thereof;

FIG. 4 is a left side view thereof;

FIG. 5 is a right view thereof;

FIG. 6 is a top view thereof; and,

FIG. 7 is a bottom view thereof.

The broken lines represent environmental elements, which form no part of the claimed design.
